WILLIAM ROSE, OF GAINSBOROUGH, ENGLAND.

APPARATUS FOR MAKING BAGS OR CONTAINERS.

1,099,130.

Specification of Letters Patent.

Patented June 2, 1914.

Application filed January 27, 1913. Serial No. 744,396.

To all whom it may concern:

Be it known that I, WILLIAM ROSE, a subject of the King of Great Britain and Ireland, of Albion Works, Gainsborough, 5 in the county of Lincoln, England, have invented new and useful Improvements in Apparatus for Making Bags or Containers, of which the following is a specification.

This invention relates to apparatus for 10 making bags, or containers, and more particularly to the "formers" upon which the bags, or containers, are made and to the presser foot, or bar, therefor, the said "formers" and presser foot, or bar, being 15 of the kind described, and illustrated in the specification of my British Letters Patent No. 3149 A. D. 1912 where the "formers" are made in two parts, one fixed and one made movable, the fixed part being secured 20 to, or formed in one with an arm fixed to a rotating spindle, or sleeve, and the movable part being secured to, or formed in one with, an arm pivotally mounted on a center toward the axis of the rotating spindle, or 25 sleeve, and the said "formers" having associated therewith a presser foot, or bar, adapted to be operated, at the proper time, to hold the longitudinal seam of the bag, or container, to the said "former."

30 In the "former" described and shown in my aforesaid British Letters Patent the pressure of the presser foot, or bar, is borne by the movable part of the "former" so that there is a tendency for the said movable part to be moved toward the fixed part of the "former" by the said presser foot, or bar, and consequently only a limited amount of pressure can be applied by the 35 presser foot, or bar, to the longitudinal seam of the bag, or container, on the said "former."

40 My present invention has for its objects to provide a "former" in which the fixed part thereof takes the pressure of the presser foot, or bar, and in providing means whereby the said presser foot, or bar, can exert greater pressure thereon so that the longitudinal seam of the bag, or container, on the said "former" is more securely held.

45 I will describe my invention with reference to the accompanying drawings in which—

Figure 1 shows in side elevation; Fig. 2 in plan, and Fig. 3 in end elevation a

"former" and a presser foot, or bar, there- 55 for constructed, arranged and adapted to operate in accordance with my said invention. Fig. 4 is a similar view to Fig. 1 but shows the parts in a different position to that shown in the said Fig. 1.

The sleeve, or spindle, 39 on which the "formers" are radially secured may be mounted in a vertical, horizontal, or angular position, but I will assume that it is mounted in such a manner that the "formers" 60 rotate intermittently in a horizontal plane. The "formers" are of a shape corresponding to the shape of the bags, or containers, to be made, such for instance as square, or rectangular. I will presume in describing 65 my invention that the bags, or containers, are to be of rectangular section.

The fixed part 52 of the "former" is secured to, or formed in one with, an arm 59 secured to the sleeve, or spindle, 39 and 70 the movable part 53 of the said "former" is secured to, or formed in one with, an arm 55 pivotally mounted on a pin 54 on the arm 59 of the said fixed part 52 of the "former." The movable part 53 is caused 75 to turn, at the proper times, on its pivot pin 54 to approach, or recede from the fixed part 52 similarly as in the arrangement shown and described in our aforesaid Letters Patent, but the position of the fixed and 80 movable parts 52 and 53 respectively are, in the arrangement in accordance with this invention, in the reverse order to that shown in the drawings accompanying my aforesaid patent, so that, as shown in the accompanying drawings, the presser foot, or bar, 85 62, is adjacent to the said fixed part 52 and the said fixed part takes the pressure when the said presser foot, or bar, is lowered. The movable part 53 is caused to turn on 90 its pivot pin 54 so as to approach slightly to the fixed part 52 to facilitate the removal of the bag, or container, from the "former" by an extension 155 of the arm 55, which extension, by the rotation of the sleeve, or 95 spindle, 39 carrying the "formers" engages, at the proper time, with an anti-friction roller 56 carried on a fixed part 71 of the apparatus. Upon the further rotation of the "former" sleeve, or spindle 39 100 the extension 155 is moved out of engagement with the roller 56 and the movable part 53, is caused to turn on its pivot pin

105

54 so as to slightly recede from the fixed part 52 by a spring 93 between the fixed and movable parts 52 and 53 respectively. A hooked projection 94 on the movable part 53 by engaging with a pin 95 on the fixed part 52 limits the movement of the movable part away from the fixed part.

5 The presser foot, or bar, 62, is hinged to the outer end of a carrier bar 81, the inner 10 end of which is mounted in bearings 82, formed on the "former" arm 59 as shown, or it may be mounted on the "former" sleeve, or spindle, 39. The carrier bar 81 is caused to turn in its bearings 82 to raise and 15 lower the presser foot, or bar, 62, by means of a suitably operated lever 83, pivotally mounted on a pin 84 carried by the forked end of an arm 159 formed in one with the arm 59 of the fixed part 52 of the "former" 20 the said lever 83 being connected to the said carrier bar 81, by toggle links, or levers, 85. A suitable length of the outer end 86 of the carrier bar 81 is made resilient by reducing its thickness transversely so that upon the 25 carrier bar 81 being turned to lower the presser foot, or bar, 62, onto the cemented longitudinal seam of the bag, or container, and pressure being exerted on the said carrier bar 81, the outer end 86 thereof will 30 yield, or bend, and a greatly increased pressure of the said foot, or bar, 62 on the seam will be thereby obtained, and upon the release of the pressure the carrier bar 81 will resume its normal shape.

35 The relative positions of the center upon which the operating lever 83 turns and the pivotal centers 89 and 90 of the toggle links, or levers, 85, connecting it to the carrier bar 81 are such that immediately before the said 40 operating lever 83 has completed its forward movement the said centers are in alinement. By a slight further forward movement of the operating lever, 83 (which further forward movement is limited by suitably ar- 45 ranged stops 91 and 92) the said centers 89 and 90 are moved slightly out of alinement so that by this means and in conjunction with the bending of the carrier bar 81, the whole of the mechanism is locked until the 50 operating lever 83 is moved in the opposite, or backward, direction. The aforesaid operating lever 83 may be actuated to raise and lower the presser foot, or bar, 62, at the required times, by any suitable arrangement 55 of cams, rods, levers, or the like, such, for example as that shown and described in my aforesaid patent.

60 It will be seen from the foregoing description that a considerable amount of pressure can be applied to the cemented longitudinal seams of the bags, which effectively assists the adhesive material to make the seam secure. If desired a guard ring, arm or other suitable means, may be employed to 65 hold the operating lever 83 in its extreme

return, or backward, position during the movement of the aforesaid "former" to its next succeeding position.

The said presser foot, or bar, 62, may, if desired, be provided at the end nearest the 70 center of the former sleeve 39, with a depression, or recess 87, preferably V-shaped in cross section, and a corresponding straight ridge or raised bar 88 be made in the fixed part 52 of the said former, so that when the 75 said presser foot or bar 62 is brought down onto the seam of the bag, and is locked in position, the aforesaid straight ridge, or bar, 88, on the former presses the paper into the said depression, or recess 87, in the said 80 presser foot or bar. By this means a preliminary crease is given to that part of the bag and the paper thereof is more easily folded along the said line when required, for instance when the bag is being folded to in- 85 close its contents, and very neat and perfectly shaped packages are produced.

The mechanism hereinbefore described and illustrated in the accompanying drawings is preferably so constructed and arranged as to permit of the necessary lubrication of the parts without danger of the lubricant coming into contact with the bags, or containers, or that portion of the "formers" upon which the bags, or containers, are 95 formed. I prefer to construct the whole of the said mechanism, with the exception of the roller 56, and the guard ring, or arm, in such a manner that each comprises a self-contained piece of mechanism and any de- 100 sired number of such self-contained pieces of mechanism can be easily affixed to the "former" sleeve, or spindle, and can be eas- 105 ily removed therefrom when required.

I claim as my invention:

1. In apparatus for making paper bags, a "former" comprising a supporting arm, a fixed part rigid therewith and a movable part pivoted thereto, together with a presser foot movable into engagement with the fixed part of the "former," substantially as de- 110 scribed.

2. In apparatus for making paper bags, a "former" comprising a supporting arm, a fixed part rigid therewith and a movable part pivoted thereto, in combination with a presser pivoted on said arm and movable into engagement with the fixed part of the "former," substantially as described.

3. In apparatus for making paper bags, a "former" comprising a supporting arm, a fixed part rigid therewith and a movable part pivoted thereto, and spring means tend- 115 ing to force said movable part away from the fixed part and engaging members on said parts limiting the extent of their separation, substantially as described.

4. In apparatus for making paper bags, a "former" comprising a supporting arm, a fixed part rigid therewith, a movable part 120

125

pivoted thereto, in combination with a presser foot pivoted on the axis of the movable part and movable into engagement with the fixed part of the "former," substantially as described.

5. In apparatus for making bags, a "former" comprising a fixed part and a movable part, an interposed spring tending to force said movable part away from said fixed part, a hooked projection on one of said parts and a pin on the other of said parts, said hook and pin being engaged with lost motion and serving to limit the extent of separation of said parts by the spring, substantially as described.

6. In apparatus of the character described, a flanged carrier sleeve, a series of self-contained "formers" thereon, each comprising a rigid bracket secured to the flange of said carrier sleeve and an extension forming a fixed part of said "former," a movable part of said "former" pivoted to said bracket, and a presser foot pivoted on said bracket and movable into engagement with said fixed portion of said "former," substantially as described.

7. In apparatus of the character described, a flanged carrier sleeve, a series of self-contained "formers" thereon, each comprising a rigid bracket secured to the flange of said carrier sleeve, and an extension forming a fixed part of said "former," a movable part of said "former" pivoted to said bracket, and a presser foot pivoted on said bracket and movable into engagement with said fixed portion of said "former," said presser

foot and movable portion of the "former" having a common axis.

8. In apparatus of the character described, a flanged carrier sleeve, a series of self-contained "formers" thereon, each comprising a rigid bracket secured to the flange of said carrier sleeve and an extension forming a fixed part of said "former," a movable part of said "former" pivoted to said bracket, and a presser foot pivoted on said bracket and movable into engagement with said fixed portion of said "former," together with an arm on said bracket and lever means pivoted thereon for bringing said presser foot into engagement with the fixed member of the "former," substantially as described.

9. In apparatus for making paper bags, a "former" comprising a supporting arm, a fixed part rigid therewith, a movable part pivoted thereto, a presser foot, a pivoted lever carrying the same and adapted to move said presser foot into engagement with the fixed part of the "former," and actuating means engaging said lever intermediate its axis and the presser foot, only that portion of said lever which lies between the presser foot and the point of engagement by its actuating means being flexible, substantially as described.

In testimony whereof I have signed my name to this specification in the presence of two subscribing witnesses.
